(57) **CLAIM**

The ornamental design for an electronic device with slidable display, as shown and described.

DESCRIPTION

FIG. 1 is a perspective view of an electronic device with slidable display showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the display portion of the electronic device with slidable display moved downward;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is an enlarged view of the encircled portion of the electronic device with slidable display of FIG. 8;

FIG. 16 is an enlarged view of the encircled portion of the electronic device with slidable display of FIG. 13;

FIG. 17 is a perspective view of the display portion of the electronic device with slidable display moved upward;

FIG. 18 is a front view thereof;

FIG. 19 is a rear view thereof;

FIG. 20 is a left side view thereof;

FIG. 21 is a right side view thereof;

FIG. 22 is a top view thereof; and,

FIG. 23 is a bottom view thereof.
